UNITED STATES PATENT OFFICE.

CLARKSON A. DISBROW, OF NEW ROCHELLE, NEW YORK, ASSIGNOR TO THE RAIL JOINT COMPANY, OF NEW YORK, N. Y., A CORPORATION OF NEW YORK.

RENEWABLE INSULATION FOR RAIL JOINTS.

Application filed September 12, 1922. Serial No. 587,789.

To all whom it may concern:

Be it known that I, CLARKSON A. Disbrow, citizen of the United States, residing at New Rochelle, in the county of Westchester and State of New York, have invented certain new and useful Improvements in Renewable Insulations for Rail Joints, of which the following is a specification.

This invention relates to sectional insulation for insulated rail joints, and more particularly to that type of insulation having readily renewable and replaceable parts at the center of the joint, whereby renewal and replacement of the insulation which is subjected to the greatest wear may be readily effected without disturbing the remaining serviceable portions of insulation.

A primary object of the invention is to meet the requirement of replacing the worn portions of the head sections of insulation under the heads of the rails near the meeting ends thereof, and also replace the worn head portion of the insulating end post which is disposed between the rail ends. While it has heretofore been proposed to renew the insulation between the heads of the joint bars and the heads of the rails, such renewals have not also involved the replacement of the worn head portion of the end post between the rail ends.

It has been found in practice that when the insulation between the bar heads and the rail heads have become damaged and worn, the upper section or head portion of the insulating end post usually is also worn out, and therefore the present invention provides a means whereby, all of the worn insulation at the ends of the rails may be conveniently renewed in one replacement operation, with the use of a relatively small amount of insulation.

Accordingly, the present invention has primarily in view the provision of a novel insulation unit for the center of the joint which permits of renewing the insulating end post at the time of renewing the worn out portions of the joint bar insulation at or adjacent the meeting ends of the rails.

A further object of the invention is to provide a renewable insulation unit wherein the head portion of the end post and the inserts of the bar head insulation are detachably interlocked in such a manner that they may be readily removed and replaced without taking apart the entire rail joint,

and without removing the good or unworn insulation. To do this it is only necessary to loosen the joint bolts, without removing them, thus effecting a great saving in time in making renewals in busy sections of track where time for maintenance and repair is limited.

With the above and other objects in view which will more readily appear as the nature of the invention is better understood, the same consists in the construction, combination and arrangement of parts herein-after more fully described, illustrated and claimed.

A preferred and practical embodiment of the invention is shown in the accompanying drawings, in which:

Figure 1 is a side elevation of a rail joint with one of the joint bars removed, exposing an insulating unit embodying the present invention.

Figure 2 is a vertical sectional view taken on the line 2—2 of Figure 1.

Figure 3 is a detail perspective view of the improved insulation unit shown in Figures 1 and 2.

Figure 4 is a view similar to Figure 2 illustrating another modification of the invention.

In carrying the invention into effect the joint bar head sections of insulation 1—1 are combined with an end post head section of insulation 2 to provide a renewable insulation unit for the center of the joint. As usual, these sections of insulation are made of hard fiber or other insulation material suitable for the purpose, and are intended to be associated with the usual joint insulation 3, which being relatively remote from the ends of the rails R, is not subjected to concentrated wear and therefore remains in a serviceable condition for a comparatively greater length of time than the insulation directly beneath and at the ends of the rails where the greatest wear is focused.

As will be observed from the drawings, the said head section 2 of the end post is of the same cross section as the rail head and substantially co-extensive in area therewith, and overlies but is detached from the body portion B of the insulating end post which can remain more or less permanently between the ends of the rails. According to the present embodiment of the invention, the said head section 2 is separate from the

bar head sections 1 which are of short length fiber sections of curved formation so as to fit the head of the joint bar at the central part of the joint. These bar head sections 5 are provided at the central portion of their outer edges 4 with the notches or mortises 5 for receiving the holding lugs 6 formed on the end post head section 2, whereby the bar head sections and the end post head section 10 have an interlocking engagement so that upon loosening the joint bars the end post head section may be readily lifted out and replaced and the bar head section of insulation likewise removed and renewed without disturbing the insulation 3.

In the construction shown in Figure 4 additional means for interlocking the head portion 2^a and the bar head insulation 1 is provided. That is to say, the end post head 20 section 2^a, in addition to having the lugs 6^a for interlocking with the notches 5 in the bar head insulation, is also provided at the end of the neck portion 7 with the laterally extending lugs 8, the same being spaced a 25 sufficient distance below the edge α of the bar head insulation sections 1, to permit of easy application of the latter when making the replacement in track. That is to say, while the primary function of the lugs 8 is to 30 prevent upward displacement of the head section of the insulation end post, nevertheless sufficient clearance γ is provided between the lugs and the edges α of the bar head insulation to permit the end post head 35 section 2^a to be lifted the distance of the space γ so as to allow the bar head inserts 1 to be passed in under the lugs 6, and then the end post insulation head section 2

dropped into position. In this way, the end post insulation 2^a not only interlocks with 40 the bar head sections 1, but the latter also prevents the end post insulation 2^a from being displaced, as previously indicated.

Other modifications of the invention will be apparent to those skilled in the art and 45 it will of course be understood that various changes in the form, proportion and minor details of construction may be resorted to without departing from the spirit of the invention or scope of the appended claims. 50

I claim:—

1. An insulating unit for rail joints consisting of a bar head section, and an end post head section having a locking engagement with the outer edge of said bar head 55 section.

2. An insulating unit for rail joints including bar head sections and an end post head section detachably interlocking with 60 said bar sections of insulation at their outer edges.

3. An insulating unit for rail joints including bar head sections having notches at 65 their outer edges, and an end post head section engaging in said notches.

4. An insulating unit for rail joints including bar head sections having notches at 70 their outer edges, and an end post head section having lugs for engaging in said notches.

In testimony whereof I hereunto affix my signature in the presence of two witnesses.

CLARKSON A. DISBROW.
